UNITED STATES PATENT OFFICE.

ORA J. WARMAN, OF ROSWELL, NEW MEXICO, ASSIGNOR OF ONE-HALF TO BEN H. BASSETT, OF ROSWELL, NEW MEXICO.

AUTOMATIC FEED FOR ACETYLENE-GAS GENERATORS.

Application filed April 24, 1920. Serial No. 376,302.

To all whom it may concern:

- Be it known that I, ORA J. WARMAN, a citizen of the United States, residing at Roswell, in the county of Chaves and State of New Mexico, have invented certain new and useful Improvements in Automatic Feeds for Acetylene-Gas Generators, of which the following is a specification, reference being had to the accompanying drawings.
- 10 This invention relates to an improved automatic feed hopper for acetylene gas generators, and an object of the invention is to provide a device of this kind which is safe in every respect and automatic in operation.
- 15 Another object is to provide an automatic feed hopper for the carbide provided with a valve for automatically controlling the carbide feed, said hopper including a pressure chamber and diaphragm connected to 20 the valve so that according to the pressure in said pressure chamber, the valve is in turn automatically controlled so as to regulate the feed of the carbide into the generator.

Another object is to provide elastic diaphragm having novel means of connection with the stem of the control valve so that the valve is automatically controlled according to the pressure in the pressure chamber.

Still another object is to provide a valve 30 cage or crow foot connection with a sleeve having a seat for the valve so as to prevent the carbide from lodging or choking the valve opening thereby always insuring a steady flow of carbide subject to the action 35 of the valve.

A further object resides in a novel construction of valve seat sleeve having means consisting of passages to permit of the passage of gas into the hopper and thence into 40 the pressure chamber, for the purpose of acting upon the diaphragm for automatically controlling the valve.

While the design and construction at present illustrated and set forth is deemed 45 preferable, it is obvious that as a result of a reduction of the invention to a more practical form for commercial purposes, the invention may be susceptible to changes, and the right to these changes is claimed, provided they are comprehended within the 50 scope of what is claimed.

The invention comprises further features and combination of parts, as will be herein-after set forth, shown in the drawings and 55 claimed.

In the drawings:—

Figure 1 is a vertical sectional view through the upper part of an acetylene gas generator showing the improved automatic feed hopper applied and shown in section; 60

Figure 2 is a vertical sectional view through the automatic feed hopper at right angles to that shown in Figure 1;

Figure 3 is a cross sectional view on line 3—3 of Figure 1 through the connection between the lower end of the feed hopper and the casing of the generator, thereby showing the plurality of passages to permit the gas to pass into the feed hopper, whereby it may then pass into the pressure chamber above, 65 and 70

Figure 4 is a horizontal sectional view on line 4—4 of Figure 1 through the pressure chamber above the diaphragm showing the location of the by-pass pipe between the hopper and the pressure chamber with respect to the means for opening the valve to start the 75 generator.

Referring more especially to the drawings, 1 designates a conventional form of acetylene gas generator tank, which has a conventional form of safety valve 2, a filling spout 3 and 4 denotes a casing adjacent the generator tank for the reception of water, as indicated. The casing has a filling spout 5 and a hose connection 6 which has a valve 7 for controlling the discharge of gas from the chamber 8 above the water in the casing 4. The tank 1 has an extension pipe 9 which carries the safety valve 2 and connecting the 80 pipe 9 and the casing 4 is a pipe 10 for the purpose of carrying the generated gas into the chamber 8. This pipe 10 is connected to the bottom of the casing 4 so that the gas passing into the chamber 8 will be thoroughly cleansed or filtered by passing through the body of water in the casing 4. A check valve 11 is carried by the lower part of the pipe 10 for preventing passage 85 of water through the pipe 10. The upper part of the generator tank 1 is provided with the usual form of gauge 12, and the lower part of the tank 1 is provided with an outlet 13, for the purpose of drawing off the refuse and slush in the bottom of the tank. 90

The upper end of the tank 1 has a flanged opening 14 into which the contracted end 15 of the automatic feed hopper 16 is threaded for the purpose of supporting the hopper in position. The hopper may be constructed 110

of any suitable metal either cast or rolled steel, suitably shaped and welded, and its upper end has an annular flange 18. Secured to the flange 18 by means of bolts 19 is a spider 17, the spider arms of which are curved as shown and depend from the flange 17^a, through which the bolts 19 pass. The lower ends of the arms 17^b of the spider connect to a collar 17^c. The pressure chamber 20 is provided and it has its lower end provided with an annular flange 21. The casing 20 and the flange 21 may be otherwise constructed to that which is shown. The flange 21 is bolted to the ring 18 by said bolts 19, there being a vibrating diaphragm 22 bolted between the flanges 21 and 18. This vibrating diaphragm may be constructed of any suitable elastic material such as rubber or other expandible or yieldable material. The space above the diaphragm constitutes a pressure chamber 23. Connected to the collar 17^c is a tubular guide 25. The lower end of this tubular guide terminates in a plurality of depending arms 26, all of which combined may be termed a "crow foot." These arms 26 are integrally connected to a sleeve 27, which is mounted in the extension or contracted neck 15. This sleeve 27 at intervals thereabout is provided with passages 28 which permit the gas from the generator to pass into the carbide receiving chamber 29 of the hopper. This sleeve 27 has a valve seat 30, with which the conical valve 31 cooperates. The valve 31 is connected to the valve stem 33 which is mounted in the tubular guide 25. The upper end of the valve stem passes through the diaphragm and is provided with upper and lower clamping plates 34 and 35, there being suitable clamping nuts 36 and 37 for holding the plates 34 and 35 in place as well as connecting the valve stem securely to the diaphragm so that when the diaphragm moves upwardly the valve will close and when the diaphragm is depressed downwardly, the valve 31 will open. A coil spring 38 is interposed between the countersunk spider and one of the plates of the diaphragm. This spring acts against one of the clamping plates of the diaphragm for the purpose of closing the valve 31.

A by-pass pipe 39 is connected at 40 to the pressure chamber casing and is in turn connected at 41 to the upper end wall of the automatic feed hopper, there being a valve 42 in said pipe 39 for the control of the gas from the hopper to the pressure chamber.

Mounted in bearings 43 of the pressure chamber casing is a rock shaft or rod 44 having a crank 45 at one end and an arm 46 adjacent its central portion adapted to act upon the upper end of the valve stem, for opening the valve in order to start the generator.

The various parts of the automatic feed hopper may be constructed of any suitable metal, certain parts of which may be constructed of steel or cast metal, preferably cast aluminum. By means of the depending arms 26 or the crow foot at the lower end of the tubular guide, the valve stem is protected from excessive frictional contact with the carbide. The design of this invention is to provide an automatic feed hopper adapted to regulate within one pound pressure.

By means of the rocking rod or shaft 44, the automatic hopper feed and the generator may be started by simply rotating the crank of the shaft causing the arm 46 to bear upon the upper end of the stem 33 and open the valve.

In the operation the rocking rod or shaft 44 is first actuated, whereby the arm 46 may bear against the upper end of the valve stem, unseating the valve 30. By this operation the carbide will enter the generator tank and the gas will be generated in the tank in the usual manner and may be conveyed from the tank to various locations for necessary use. Gas from the tank will pass through the passages 28 and percolate through the carbide in the feed hopper and by opening the valve 42 gas will be permitted to enter the pressure chamber 23 by way of the bypass pipe 39. The pressure in the pressure chamber is designed to be constant, and at times the pressure in the feed hopper equals the pressure in the pressure chamber. The valve 42 is closed upon the attaining of the required pressure in the chamber above the diaphragm. The valve 30 is designed to open sufficiently to permit a requisite supply of carbide to enter the tank. As the gas in the tank is excessively drawn off, thereby decreasing the gas in the generator and hopper below the diaphragm, it leaves the constant pressure in the pressure chamber 23 slightly relatively greater, and causes the carbide feed valve to open, allowing a supply of carbide to enter the tank and thereby increase the generation of gas.

As the gas in the tank is being generated and when it is drawn off in required amounts, the gas slightly decreases in the hopper below the diaphragm. This result necessarily causes a constant pressure in the pressure chamber which at times is equaled by the pressure in the hopper below the diaphragm. As it is the aim to maintain the pressure in the generator below the diaphragm substantially one pound pressure less than the pressure in the pressure chamber, the pressure below the diaphragm will substantially equal the pressure above the diaphragm. When the gas decreases in the generator and the pressure above the diaphragm remains constant and consequently slightly greater than the pressure below the

- diaphragm, the carbide feed valve 31 will open allowing carbide to slowly feed though the pressure below the diaphragm is substantially equal to the pressure above the diaphragm. At this time the valve 31 will close and so on automatically opening and closing, keeping the pressure in the generator about one pound pressure less than the pressure in the pressure chamber. Furthermore, 10 there cannot be at any time a greater pressure generated in the generator below the diaphragm than the pressure in the pressure chamber, thereby providing an acetylene gas generator which has been found safe and fool proof. When the valve 31 is closed the passages 28 remain open so as to permit a supply of gas to enter the chamber below the diaphragm, in order to substantially equal the pressure in the pressure chamber so that the generator can operate automatically.
- The invention having been set forth, what is claimed as new and useful is:
1. In an automatic feed hopper for acetylene gas generators, a gas generator tank, a feed hopper having a communicative connection with said tank, said connection including a valve seat, a valve cooperating with said seat to control the flow of carbide from the hopper to the tank, said hopper having a pressure chamber casing mounted thereon, a communicative connection between said pressure chamber and the hopper, an elastic diaphragm between the pressure chamber and the feed hopper to be acted directly upon by the pressure both in the hopper and in the pressure chamber, said diaphragm being connected with the valve, and tensioning means below the diaphragm acting to normally close said valve.
  2. In an automatic feed hopper for acetylene gas generators, a gas tank, a feed hopper having communicative connection with said tank and provided with a pressure chamber, an elastic diaphragm between the pressure chamber and feed hopper, a valve operatively connected to said diaphragm for controlling said connection, said connection including gas passages between the tank and the hopper, a communicative connection between the pressure chamber and the hopper, said diaphragm adapted to be acted directly upon by the pressure in both the hopper and said pressure chamber.
  3. In an automatic feed hopper for an acetylene gas tank, a hopper connected to said tank, a valve controlling the carbide from the hopper through said connection, a pressure chamber, an elastic diaphragm in the lower part of the pressure chamber and connected to the valve, the connection between the hopper and the tank having gas passages to permit gases from the tank to pass into the hopper, means for permitting the gas from the hopper to enter the pressure
  - chamber, and tensioning means cooperating with the diaphragm to hold the valve seated, said elastic diaphragm being between the hopper and the pressure chamber to be acted directly upon by the pressure in both the hopper and the pressure chamber.
  4. In an automatic feed hopper for an acetylene gas tank, a hopper connected to said tank, a valve controlling the carbide from the hopper through the connection, a pressure chamber, an elastic diaphragm in the lower part of the pressure chamber and connected to the valve, the connection between the hopper and the tank having gas passages to permit gas from the tank to pass into the hopper, means for permitting the gas from the hopper to enter the pressure chamber, and tensioning means cooperating with the diaphragm to hold the valve seated, and manual means for actuating the valve for starting the generator, said elastic diaphragm being between the hopper and the pressure chamber to be acted directly upon by the pressure in both the hopper and the pressure chamber.
  5. In a device as set forth, an acetylene-generator tank, a feed hopper for carbide mounted on and connected to the tank, gas communications between the tank and the hopper, a valve seat and valve for controlling the carbide from the hopper to the tank, an elastic diaphragm connected to the valve and located between the pressure chamber and the hopper, whereby the pressure of gas in the pressure chamber and the pressure in the hopper may act directly upon the diaphragm to operate the valve, and tensioning means acting direct upon the elastic diaphragm when the pressure of gas in the pressure chamber is decreased to close the valve.
  6. In a device as set forth, an acetylene generator tank, a feed hopper for carbide mounted on and connected to the tank, gas communications between the tank and the hopper, a valve seat and valve for controlling the carbide from the hopper to the tank, an elastic diaphragm connected to the valve and located between the pressure chamber and the hopper, whereby the pressure of gas in the pressure chamber and the pressure in the hopper may act directly upon the diaphragm to oscillate the valve, and tensioning means acting direct upon the elastic diaphragm when the pressure of gas in the pressure chamber is decreased to close the valve, a connection between the hopper and the gas pressure chamber, said valve having a stem, a guide for the stem, the lower end of the guide having means to prevent the carbide from choking in the connection between the hopper and the tank.
- In testimony whereof I hereunto affix my signature.

ORA J. WARMAN,
